Primary Examiner — Steven J Czyz(74) *Attorney, Agent, or Firm* — Smyrski Law Group, A.P.C.(57) **CLAIM**

The ornamental design for a crutch connector arrangement, as shown and described.

DESCRIPTION

FIG. 1 is a perspective view of a crutch connector arrangement, showing our new design with the two pieces joined; FIG. 2 is a perspective view of the crutch connector arrangement, shown with the two pieces separated;

FIG. 3 is a perspective view of just one of the two pieces of the crutch connector arrangement, shown separately for ease of disclosure;

FIG. 4 is a front view thereof;

FIG. 5 is a rear view thereof;

FIG. 6 is a right side view thereof;

FIG. 7 is a left side view thereof;

FIG. 8 is a top plan view thereof; and,

FIG. 9 is a bottom plan view thereof.

The broken lines depict portions of the article and environment that form no part of the claimed design.

1 Claim, 7 Drawing Sheets(56)
